UNITED STATES PATENT OFFICE

2,374,419

RAZOR BLADE SHARPENER

William Thomas Clarke, Lion's Head,
Ontario, Canada

Application January 24, 1944, Serial No. 519,525

4 Claims

(Cl. 51—158)

This invention relates to razor blade sharpeners and more particularly to a vitreous safety razor blade sharpener and edge aligner.

Specifically, the invention contemplates a base or sharpening element of a vitreous material having a semi-cylindrical concavity in the top surface, a main frame carried by the base having an oscillating frame pivotally mounted thereto and means for functioning integrally with the oscillating frame, to maintain sharpening contact between the blade and the sharpening element, said means being adjustable separately of the arc defining pivot points of the oscillating frame.

One of the principal objects of this invention is to provide means for adjusting the tension between the blade and the sharpening element whilst maintaining a uniform arc concentric with the semi-cylindrical surface of the sharpening element.

Another object of the invention is to provide a blade sharpener of the type described which will facilitate the operations of placing the blade in the sharpener and the removal of the blade therefrom.

Still another object is to facilitate the sharpening operation itself, the invention proposes a rotatable, fingertip control on the actuating arm which is slidable against the base and is therefore automatically path-defining, requiring an absolute minimum of manual dexterity.

Still other objects of a more general nature are, to provide an efficient, durable and inexpensive device of the character set forth for the purpose of improving the shaving quality and prolonging the useful life of all flexible thin-type safety razor blades.

With the above noted and other objects in view which may appear as the description proceeds the invention resides in the novel construction, combination and arrangement of cooperating parts as hereinafter more specifically set forth, claimed and shown in the accompanying drawings forming part of this application, and in which:

Fig. 1 is a side elevational view of my invention.

Fig. 2 is a transverse sectional view along the line 2—2 of Figure 1.

Fig. 3 is a perspective view of the base or sharpening element.

Figs. 4 and 5 illustrate the blade holder tension adjustment members.

Fig. 6 is a perspective view of one side member of the main frame.

Fig. 7 is a perspective view of one sleeve in which is journaled the oscillating frame.

Fig. 8 is a transverse sectional view along a line indicated as 8—8 of Figure 2, but not sectionalized.

Fig. 9 is a perspective view of one arc defining bar.

Fig. 10 is a perspective view of the cover plate of the main frame.

Fig. 11 is a fragmentary view of the hinged connection of the actuating arm.

Referring more in detail to the drawings in which similar reference characters designate corresponding parts throughout the several views it will be seen that the invention includes a base or sharpening element 10, made of a suitable vitreous material and having a semi-cylindrical concavity cut in its top surface to form the sharpening surface 11, against which the razor blade is oscillated. On each side of the sharpening element 10, at one end thereof a drilled hole 12, is located, to receive in pivotal engagement the cylindrical studs 13, secured to arms on each of the side members 14, of the main frame.

The main frame consists of a pair of similar side members 14, joined by a top member or caps-piece 15, which is disposed across the said side members and secured thereto by four set screws 16. The side members are in pivotal engagement with the sharpening element 10 as hereinbefore described and frictionally held in the closed position, that is, in the position shown in Figure 1, by the tensional grip of the curved lugs 17. A shouldered sleeve 18, is carried in the orifice 19, located centrally of each side member; it is important to note that when the main frame is in the closed position the sleeve 18 is concentric with the circle formed, in part, by the sharpening surface 11. The caps-piece 15, is slotted at 20, to permit the blade holding adjustment bolt to oscillate therewith as will be explained in detail later. A depression 21 in the under surface of one end of the caps-piece provides means for raising the main frame to its open position.

An oscillating frame 22, the trunnions 23 of which are journaled in the sleeves 18, is carried by the main frame. The oscillating frame has a centrally disposed threaded orifice 24, in the transverse section to engage the tensional adjustment bolt. The inwardly extending lugs 25, have orifices therein through which slide freely the dowel-like ends of the screws 26.

The blade retainer consists of an inverted T 27, preferably made of rubber although other resilient material may be used, a channel shaped

socket 28, to which the T piece 27, is secured and a frame 29, as seen particularly in Figure 2. The aforementioned screws 26, secure the socket and frame together. The transverse center portion of this frame has an orifice 30, therethrough through which the restricted end of the tensional adjustment bolt extends.

The blade retainer is adjustably mounted on the oscillating frame by means of this tensional adjustment bolt 31, which passes down through the slot 20, in the capspiece, is threadably engaged in the oscillating frame 22, and whose restricted extremity passes through the orifice 30, until the shoulder thereof abuts the frame 29. A thumbscrew 32, is threadably attached to the restricted extremity to secure the frame 29, to the member 31. The dowel-like extremities of the screws 26, which are slidable through the flanges 25 prevent lateral movement of the blade retainer whilst permitting vertical movement thereof. It will be noted (Figure 2) that the frame 29, has an integrally formed arm 33, extending beyond the side wall of the sharpening element 10, and to which, at the extremity is hinged at 34 an actuating arm 35, terminally provided with a rotatable, recessed button 36, for fingertip control of the oscillating mechanism. The rivet 37, is arranged to slide against the side wall of the sharpening element when the actuating arm is operated.

To restrict the movement of the oscillating frame I have provided two arc definers 38, mounted transversely on the main frame and secured thereto by the set screws 16, the rounded edge 39, thereof abutting the oscillating frame when it has reached the predetermined upper limits of its arc.

The mechanical functioning of the related parts is as follows: by raising the main frame, that is pivoting it upward around the studs 13, the assembly is removed from the concavity so that the razor blade may be inserted therein. The assembly is then closed so that the blade retainer is evenly placed over the razor blade. The sharpening tension is determined by the space existent between the concavity and the member 27, and is adjustable by rotating the anti-clockwise threaded adjustment bolt 31, to the required position and then tightening the thumb nut 32, to the end that the blade retainer is secured to the oscillating frame in the position relative to the surface of the concavity, determined by the user. The actuating arm is then oscillated as hereinbefore described thus oscillating the frame 22, and the blade retainer carried thereby and causing the razor blade to slide against the wall of the sharpening element. The sharpening of one side accomplished the blade is reversed and the procedure repeated.

It is believed that the structure and advantages of the device may be apparent from the foregoing paragraphs taken in conjunction with the accompanying drawings without further detailed description.

While the preferred embodiment of the invention has been disclosed it is understood that minor changes in the detail of construction and arrangement of the co-operating parts may be resorted to within the scope of that which is claimed without departing from the spirit of the invention.

I claim:

1. A razor blade sharpener comprising a sharpening element of vitreous material having a semi-cylindrical sharpening surface formed in the top, a frame pivotally attached to said sharpening element in covering relation to the sharpening surface, an oscillating frame carried by said first named frame, a blade retainer carried by said oscillating frame, said retainer being adjustable towards and from the sharpening surface, a resilient member carried by the retainer adapted to yieldably press the blade held thereby against the sharpening surface and means for adjusting the tension of said resilient member against the blade.

2. A razor blade sharpener comprising a sharpening element of vitreous material having a semi-cylindrical sharpening surface formed in the top, a frame pivotally attached to said sharpening element in covering relation to the sharpening surface, an oscillating frame carried by said first named frame, a blade retainer carried by said oscillating frame, said retainer being adjustable towards and from the sharpening surface, a resilient member carried by the retainer adapted to yieldably press the blade held thereby against the sharpening surface, and an adjusting screw connected to said retainer and having threaded engagement with said oscillating frame, said screw extending through a slot in the first named frame for adjusting the tension of the resilient member against the blade.

3. A razor blade sharpener comprising a sharpening element of vitreous material having a semi-cylindrical sharpening surface formed in the top, a frame pivotally attached to said sharpening element in covering relation to the sharpening surface, an oscillating frame carried by said first named frame, a blade retainer carried by said oscillating frame, said retainer being adjustable towards and from the sharpening surface, a resilient member carried by the retainer adapted to yieldably press the blade held thereby against the sharpening surface, means for adjusting the tension of said resilient member against the blade, and adjustable means carried by said first named frame for limiting the movement of said oscillating frame.

4. A razor blade sharpening device comprising a block of vitreous material having a semi-cylindrical recess in its top face forming a sharpening surface, a pair of side members pivotally connected at one end to the sides of said block having bearings intermediate their ends concentric to the arc of the recess, a top plate connecting said side members having a central longitudinal slot, an oscillating frame having trunnions journaled in the bearings of the side members, a blade retainer member mounted on said oscillating frame for movement towards and from the sharpening surface, an adjusting screw connected to said retainer member and threadedly mounted in said oscillating frame having its upper end extending through the slot in the top plate, and a resilient block of material carried by said retainer member adapted to yieldably press a razor blade placed between the block and sharpening surface into co-acting relationship with the sharpening surface during movement of the oscillating frame.

WILLIAM THOMAS CLARKE.
